UNITED STATES PATENT OFFICE.

SAMUEL P. BUSH, OF COLUMBUS, OHIO.

CAR-COUPING.

1,248,803.

Specification of Letters Patent.

Patented Dec. 4, 1917.

Application filed April 10, 1916. Serial No. 90,176.

To all whom it may concern:

Be it known that I, SAMUEL P. BUSH, a citizen of the United States, and a resident of Columbus, in the county of Franklin and State of Ohio, have invented certain new and useful Improvements in Car-Couplings; and I do hereby declare the following to be a full, clear, and exact description of the invention, such as will enable others skilled in the art to which it appertains to make and use the same.

My invention relates to an improvement in car couplings, the object being to provide a construction that will combine simplicity with maximum strength of parts, also that will provide for greater certainty of some operations under all conditions than has heretofore been possible, and it consists in the parts and combination of parts and in the details of construction as will be more fully described and pointed out in the claims.

In the accompanying drawings, Figure 1 is a view in section through a draw head and knuckle, the locking block and lifting lever for the latter being in elevation; Figs. 2, 3 and 4 are similar views showing the successive positions of the locking block and knuckle during the upward movement of the locking block; Fig. 5 is a similar view showing the knuckle in a partly open position and the locking block resting on the tail of the knuckle; Figs. 6 and 7 are views of the knuckle; Figs. 8, 9 and 10 are views of the locking block; Fig. 11 is a view in perspective of the coupling, the guard arm side of the head being broken away, and Fig. 12 is a view in section through the guard arm.

Fig. 14 represents the draw head of the coupling provided with ears 15 having oppositely disposed lugs 16 which are integral with the ears 15 and head 14, the outer margin of the lugs being circular as shown in Fig. 11.

The draw-head is provided intermediate the ears with the stops 17^a against which the shoulders 18^a on the knuckle abut when the latter is in closed position, thus assisting the other parts to be hereinafter referred to in taking the buffing stresses. The knuckle 19 is recessed as at 20, on its upper and lower faces, to receive the lugs 16 on the ears of the draw-head, and the said recesses 20 are so located and of such shape that the wall 21 thereof bearing against the

lugs 16, and the shoulders 18^a bearing against the stops or abutments 17^a take, as before explained, the buffing stresses. The rear inner surface 18 of the wall 21 of the recess, terminates, in a position to take part of the pulling stresses, thus relieving the pivot pin of much stress in pulling.

The ears 15 and lugs 16 are provided with a pin hole, and the knuckle 19 is provided with a corresponding hole for the passage of the pin which locks the knuckle to the draw-head.

The knuckle 19 is provided with a tail 22, the upper and lower faces of which are inclined upwardly and rearwardly as shown in Fig. 7. The upper face is provided at its outer edge with a rib 23 adapted to engage a shoulder or surface on the locking block for lifting and supporting the latter as will be hereinafter more fully explained.

The locking block 24 which is shown detached in Figs. 8, 9 and 10, is provided with a depending leg 25, terminating in a toe 26, which projects horizontally, or at a slight inclination from the lower end of the leg. The underside of this leg, or the toe at the end of the leg, has an inclined surface as at 27, extending about half the length of the toe, and beyond this, the lower face of the toe is approximately horizontal. The locking block 24 is provided with a shoulder or surface 28 adapted to be engaged by the rib 23 on the knuckle tail, and it is also provided at its upper end with a horizontally projecting lip 29 adapted to bear against the ribs 30 formed on the inner face of the side wall of the draw-head. The draw-head is provided in its throat at one side with an inclined seat or shelf 31 extending in the direction of the length of the coupling and adapted to support the locking block in its lock set position.

Pivoted to a bracket 32 depending from the guard arm of the draw-head, is the lever 33, the rounded free end of which is adapted to engage the lower face of the toe 26 of the locking block 24, for lifting the same, the lower end of the coupling head having an opening therein for the passage of the lever 33. This lever is connected with a pull-rod 34 which in turn will be connected with an actuating lever not shown.

Fig. 1 shows the locking block in its normal locking position; Fig. 2 shows it slightly raised, but not enough to release the knuckle; Fig. 3 shows it resting on the shoul-

der 31 or in set position; Fig. 4 shows it in its highest position with the knuckle thrown to open position and Fig. 5 shows the knuckle partly closed with the locking block 5 resting thereon.

In describing the action of the lock in going onto its set, I will first describe the sliding action due to the inclination of the surface 27, as it can go onto its set in this 10 way, and then refer to the action of the toe 26 in tilting the lock, the latter adding to the positiveness of the operation.

When the knuckle is closed and locked, the locking block rests well down in the head, 15 so that the portion of the block above shoulder 28 is in the plane of the tail of the knuckle. To release the knuckle, a pull is exerted on rod 34 which actuates lever 33 in a direction to carry the free end of the latter into contact with the lower face of the extension 25 of the locking block. As the lever is moved, its free end engages and slides on the inclined surface 27 of the locking block thus tilting the locking block from 20 the position shown in Fig. 2 to that shown in Fig. 3, and in so doing the lower inclined surface 27 of the locking block slides on the end of the lever 33, thus bringing the lower edge of the extension 25 of the block 25 in the plane of and over the lock set 31. If for any reason the block fails to slide into position over its lock set seat 31, a continued upward movement of the lever 33 will carry the toe 26 of the extension 25 of the 30 lock, into engagement with the tail of the knuckle and thus positively tilt the lock until the lower edge of the extension is over the seat 31. By now releasing the lever 33, the locking block will settle down and rest 35 on its seat 31. If the knuckle be now thrown to open position by any means other than the lever 33, the rib 23 on the top of the knuckle tail will, during said opening movement, come in contact with the shoulder 28 40 on the locking block, at one side of the center of gravity of the latter, thus elevating the block and causing it to tilt or swing away from the seat 31. This swinging or tilting movement is limited by the end of 45 the toe 26 contacting with the surface 35 of the locking block housing. This surface 35 is continued up at the rear in the form of a beveled or inclined extension 35^a, and at the extreme rear by the narrow strip or 50 surface 35^b against which the toe bears and prevents any part or edge of the locking block from moving over into the plane of the top edge of the surface 35. By now closing the knuckle, after the same has been wholly 55 or partly opened, the lock continues to ride on the rib 23 and is gradually lowered until the knuckle swings clear of the locking block thus permitting the latter to drop into position shown in Fig. 1 and lock the knuckle 60 in its closed position.

If it be desired to throw the knuckle to open position by means of the lever 33, a continued pull on rod 34 will elevate the locking block until the top surface of the toe 26 of the extension 25 of the locking block 70 engages the lower inclined or cam face of the knuckle tail, and a continued movement will then forcibly move the locking block to its highest position and throw the knuckle to its open position. During this 75 movement the upper end of the locking block will tilt inwardly or toward the left, thus causing its lip 29 to engage and ride on the ribs 30, while the front and rear walls of the housing prevent any endwise or 80 vibratory movement of the block.

It will be observed that the locking block is wholly inclosed within the housing and that provision is made for guiding both ends of the locking block in its upward and 85 downward movements.

Again the lock set being at one side of the housing and extending in the direction of the length of the draw-bar, the locking block cannot be dislodged from its lock set 90 position by impacts or blows incident to coupling.

The means for tilting the locking block and moving it to its lock set position are simple and positive. When the knuckle is 95 closed, the lock descends to its lowest position in locking the knuckle and is firmly supported by the walls of the housing, and with the lock in this position, the abutments under compressive stresses on the knuckle 100 and draw-head co-act, as do the surfaces 19 of the knuckle and the surfaces of the lug 16 under pulling stresses, thus relieving the pivot pin, to a very large degree, from 105 stresses.

While I prefer to actuate the locking block from below, as described, it may be provided, as shown in Fig. 9 with means for its attachment to a lifting chain.

It is evident that many slight changes 110 might be resorted to in the relative arrangement of parts shown and described without departing from the spirit and scope of my invention, hence I would have it understood 115 that I do not wish to confine myself to the exact construction and arrangement of parts shown and described, but,—

Having fully described my invention what I claim as new and desire to secure by Letters-Patent, is:—

1. In a car coupling, the combination of a draw head having integral lugs for supporting and taking the pulling and buffing stresses of the knuckle, and also provided with stops intermediate the lugs, a knuckle 125 having recessed seats to receive the said lugs and adapted to turn on the latter, and also having shoulders to engage the said stops, and a locking block for the knuckle.
2. In a car coupling, the combination of 130

a draw head having a lock set seat, a knuckle, a locking block having a depending extension terminating in a toe the lower face of which is inclined throughout a portion of its length, the upper face of the said toe adapted when the locking block is lifted, to engage the underside of the tail of the knuckle, whereby the locking block will be tilted in a direction away from the 10 knuckle and over the seat, and which by its continued upward movement throws the knuckle to open position, and a lever to engage the inclined underface of the toe for lifting the locking block and also for assisting in seating the same.

3. The combination of a draw head, a knuckle and a locking block the latter terminating in a toe the lower face of which is inclined throughout a portion of its length 20 and is approximately horizontal throughout the remaining portion, the draw head having surfaces above and below the knuckle for guiding both ends of the locking block

and also provided with a rest for the locking block which conforms in shape to the 25 lower face of the toe, and on which said lower face rests when the locking block is in its lowermost position.

4. In a car coupling, the combination of a draw head having a lock set seat, a knuckle 30 and a locking block having a depending extension terminating in a toe, which when the block is lifted engages the underside of the tail of the knuckle and tilts the block in a direction away from the knuckle and over 35 the seat, and which also by its continued upward movement throws the knuckle to open position.

In testimony whereof, I have signed this specification in the presence of two subscribing witnesses.

SAMUEL P. BUSH.
